UNITED STATES PATENT OFFICE.

CLAIR D. LAKE, OF BINGHAMTON, NEW YORK, ASSIGNOR TO THE TABULATING MACHINE COMPANY, OF ENDICOTT, NEW YORK, A CORPORATION OF NEW JERSEY.

PRINTING TABULATOR.

Application filed March 26, 1924. Serial No. 701,941.

This invention has for its object the improvement of printing tabulators heretofore devised by me to the general end that certain additional functions may be performed by the machine.

One object of the present invention resides in the provision of means for preventing the printing or listing of each individual item when the machine is set for listing but at the same time permitting a total of the individual items to be printed at the time the machine operates to take a total.

A further object of the present invention resides in the provision of means for printing accumulated sub-totals from one or more of the counters without resetting the counter or counters to zero. Such an operation may take place at the end of a sub-group or, if desired, the accumulated sub-total may be printed at the bottom of one sheet and repeated at the top of the next printed sheet for checking purposes.

In the drawings,

Figs. 1 and 2 taken together show a circuit diagram of the machine.

Fig. 3 shows a part of the mechanism of the machine.

Fig. 4 is a detail of certain of the contact devices.

The circuit diagram (Figs. 1 and 2) shows the usual circuits of an electrically controlled tabulating machine of the type now on the market and commonly known as the Hollerith printing tabulator. This diagram and the operation of the machine are more fully set forth and described in my copending application, Serial No. 639,153, filed May 15, 1923. The general mechanism of this tabulator is shown in my previous Patent No. 1,379,268, to which reference may be had for a more complete understanding of the details of the machine.

In order to prevent the listing of individual items when the machine is set for listing and at the same time to provide for the printing of totals I provide certain supplementary controlling circuits as will now be described.

Referring first to Fig. 3 of the drawings, the shaft 355 is that shaft in my machine which is rocked during the reset cycle to rock the total-taking contacts into engagement with their stepped cams and thereby

control the taking of a total. This shaft 55 from point of function corresponds to the shaft marked 78 in my patent heretofore referred to.

During each totalling operation the shaft 355 in Fig. 3 is rocked in a clockwise direction by means of the cam 353. This movement is utilized to close certain contacts for permitting the taking of a total of the items, which contacts normally remain open during listing operations inasmuch as during listing, shaft 355 is in the position shown in Fig. 3.

The contacts referred to above comprise three contacts, 400, 401 and 402. They are suitably mounted upon a fixed frame member 404 and arranged to project upwardly therefrom, as shown in Fig. 3. A suitable crank arm 406 depending from the total-taking shaft 355 carries an insulated contact actuator 407 which is arranged in alignment 75 with the longer of the pair of contacts. Upon the rocking of shaft 355 in totalling operations, the contacts 400, 401 and 402 are all closed and during listing these contacts all remain open, as shown in Fig. 3. 80

Referring now to the circuit diagram (Figs. 1 and 2) it will be noted that three non-list switches 409, 410 and 411 are provided. These switches (when open) provide for the suppressing of listing on 85 counters numbered 3, 4 and 5. It will be understood that similar switches could be used on counters 1 and 2, if desired. Contacts T^a and T^b are now used in the machine and are both closed when listing, contacts 90 T^a supplying current through wire 104 to common bars 103. Contacts T^b in place of being connected to the common bars 125, as in the former construction, connect to a lead 126^a which, through individual non-list switches 409, 410 or 411, may be selectively connected to leads 412, 413 and 415, respectively, these leads extending to common bars 103^a, 103^b and 125, said bars being common bars on counters 3, 4 and 5, 100 respectively. By closing any or all of the switches 409, 410 or 411, listing of each item will be performed as heretofore. If it is desired to suppress the listing, the particular switch 409 on any desired counter is opened 105 thus suppressing the supply of current to the common bars during listing and thereby preventing the printing of items entered

into in that particular counter. In order to effect the printing of a total from these counters when totals are drawn off from the machine, supplementary leads 416, 417 and 418 are provided. These leads extend respectively to the contacts 400, 401 and 402 and from the other side of these contacts a suitable common lead 419 extends to the cam contacts P^3 . Cam contacts P^3 close 10 when totals are being taken and inasmuch as contacts 400, 401 and 402 are closed during this period current will be supplied to the common bars 103^a, 103^b and 125 permitting a total or totals to be printed of the 15 amounts standing on the counter. The switch 237 is a switch heretofore provided in these machines for preventing the printing of a total and is called the nontotal print switch. If this switch is opened, the 20 machine may be arranged so as to prevent the printing of totals when the machine is set for either listing or totalling.

The means for printing accumulated sub-totals will now be described. Referring 25 particularly to Fig. 1 of the circuit diagram, 243 is the usual reset key of the tabulator. This key, when closed, establishes a circuit between binder post 4 and binder post 6 and initiates the resetting of the tabulator. In 30 the present construction a pair of leads 431 and 432, are connected to these binder posts and lead to contacts 433 which are operated by a sub-total key 434. Thus the sub-total key control contacts 433 are in multiple 35 with the usual reset contacts 243. In addition to the contacts 433, the sub-total key 434 is adapted to close supplementary sub-total contacts 435.

In addition to the usual relays heretofore 40 used in the machine, a so-called sub-total relay 436 is provided. Depression of sub-total key 434 energizes the sub-total relay 436, current flowing as follows: from left side of line 82 through wire 437, contact point 438 of relay 436, wire 439, contacts 435 now closed, wire 440, to junction with the wire 441 (Fig. 2), thence back through wire 441, through the coil of relay 436, wire 442 to binder post 2, thence through clutch 45 magnet 233, binder post 3, contacts 234, through the shunt circuit 431, 433, 432, around the reset key contacts 243 and thence to binder post 6 and back to line. As soon 50 as the armature of relay 436 is attracted against point 438 a holding circuit is established for the relay 436 thus permitting the release of the sub-total key 434. The circuit just traced initiates and maintains the operation of the motor circuit for the reset 55 motor RM just as if the usual reset key 243 were operated.

In the diagram, 128 are the usual zero 60 button contacts. Attached to the side of these contacts which connect with the common bars 127 are supplementary leads 444

which extend to switch points adapted to connect accumulated subtotal switches 445 which are respectively connected to a lead 446 leading to the junction of wires 440 and 441.

Should it be desired to print an accumulated sub-total on any counter, the reset button of that counter is thrown out, which, through the bell crank 129 heretofore used, opens the respective contacts 128. Should it be desired to print an accumulated sub-total the desired switch 445 on the counter where an accumulated sub-total is to be printed is closed thus connecting line 446 with connection 444. Then by depressing 80 sub-total key 434 during a totalling operation a circuit will be provided for printing the accumulated sub-total. Starting at common bar 103^a this circuit extends through printer magnets 102, stepped cam contacts 112, common bar 127, wire 444, switch 445, wire 446, wire 441, wire 437 and back to left side of line. At the completion of the accumulated sub-total printing operation, sub-total relay 436 will be deenergized by 90 the opening of contacts P^1 (Fig. 1). At the end of any desired number of accumulated sub-total printing operations the counter on which accumulated sub-totals are carried can be reset by shifting the reset clutch button in the usual manner.

The general arrangement of the tabulator printing devices and the resetting buttons which disconnect the resetting means are shown in my previous patent No. 1,379,268, 100 and also shown in my copending application, Serial No. 639,153, filed May 15, 1923.

What I claim is—

1. A tabulating machine of the printing type having in combination with provisions 105 for preparing lists of individual items derived from perforated records and for printing the totals of said items, automatically operable means for suppressing the listing of individual items in certain columns, said means having provisions for automatically permitting the machine to print totals of the items in said columns, the listing of which has been automatically suppressed.

2. A tabulating machine of the printing 115 type having in combination with means for listing individual items and means for printing the totals thereof, means for automatically suppressing the listing of items in certain columns, and permitting the printing 120 of the totals thereof and means for rendering the last mentioned means ineffective whereby the items may be all listed and the totals thereof printed.

3. A tabulating machine having in combination means for printing individual listed items and totals thereof, electrical circuits for controlling the operation of said printing means, and means operable to automatically render said circuits ineffective to con- 125 130

trol the printing means during listing operations, said means having automatically operable provisions for rendering said circuit devices effective for control of the printing devices during totalling operations whereby listing of individual items is suppressed and the printing of the totals thereof is permitted.

4. In a tabulating machine having printing devices for printing listed items derived from perforated record cards and totals derived from accumulating counter devices, electrical circuits for controlling said printing devices, contact devices in said circuits, and means for differently automatically operating the said contact devices during listing operations and totalling operations to render the circuit devices ineffective during listing operations and to permit the same to be effective during totalling operations whereby the listing of individual items is suppressed and the printing of totals is permitted.

5. A tabulating machine of the electrically controlled printing type including in combination, printing circuits adapted to control printing devices during both item listing and total printing operations, means for automatically interrupting said circuits during listing operations and for maintaining said circuits during totalling operations whereby the listing of individual items is suppressed while totals thereof may be printed.

6. A tabulating machine of the electrically controlled printing type including in combination, printing circuits adapted to control printing devices during both item listing and total printing operations, means operable at the will of the operator for alternately permitting either the establishment of said circuits both during item listing and totalling operations or for suppressing the establishment of said circuits during item listing operations while permitting their establishment during total printing operations.

7. The invention set forth in claim 5 in which switch means is provided for maintaining said circuits irrespective of the operation of the interrupting means whereby items and totals may be both printed at will.

8. A tabulating machine of the printing type having printer magnet circuits, means for automatically maintaining the said circuits open during listing operations, and means for automatically closing said circuits during totalling operations.

9. A tabulating machine of the multiple counter printing type in which listing of individual items and printing of totals of said items is effective, means for entirely suppressing the listing of the items entered into certain of the counters only and means for printing totals of items entered into all counters.

10. A tabulating machine of the multiple

counter printing type in which items are both entered into the counters and individually listed, means for suppressing the listing of all items which are entered into certain selected counters, and means cooperating with the aforesaid means to permit printing of totals from said selected counters.

11. A tabulating machine of the multiple counter printing type having electrically controlled printing devices for listing items and printing totals, a plurality of switches, one for each counter for suppressing the listing of the items which are entered into the counters, and contact devices adapted to be closed during totalling operations to permit the printing of totals of items whose listing has been suppressed.

12. In a tabulating machine of the printing type including a plurality of counters, means for printing the totals and means for resetting the counters to zero, a plurality of sub-total switches, means controlled thereby for initiating sub-total printing operations upon one or a plurality of the counters, said last mentioned means including provisions for rendering such printing means effective to print accumulative sub-totals.

13. In a tabulating machine in which sets of separate items are concurrently derived from perforated record cards and in which means is provided for effecting printing operations of the various items at each card cycle and for spacing the paper between each printing operation in combination with devices operable at the will of the operator for selectively suppressing item printing operations upon selected portions of the record while permitting normal item printing operations upon other portions of the record and means associated with said devices for permitting the machine to print totals of the items whose listing has been suppressed.

14. In a tabulating machine of the printing type, a plurality of counters from which totals are printed, means to effect the disengagement of certain selected counters from the reset devices to suppress the printing of totals from said selected counters and means for permitting the printing of sub-totals from said selected counters, said means including sub-total switches and circuits controlled thereby for initiating a resetting and printing operation, said circuits also having provisions for introducing the printing devices of the desired counter into a circuit.

15. A tabulating machine including a plurality of accumulator devices, means for individually resetting certain selected devices, printing devices for printing totals of amounts set up upon said accumulator devices, means normally operating to suppress the effective operation of the printing devices which are controlled by said selected

devices and means for rendering said last mentioned means ineffective when accumulative sub-totals are to be printed.

16. In a tabulating machine having accumulator devices, means for individually resetting certain selected devices, printing means controlled by said selected devices whereby totals are normally printed only when the accumulator devices are reset and selectively operable means for rendering said printing devices operative to print sub-totals.

17. A tabulating machine including total taking mechanism and a plurality of accumulators, resetting means individual to each accumulator and individual control means therefor to effect reset on a total taking operation and means for detachably associating the individual control means with the resetting means to permit totaling in connection with desired accumulators without reset thereof.

18. A tabulating machine including a

plurality of accumulators and printing mechanism associated therewith, means for selectively suppressing printing on any of said accumulators on a total taking operation and means for effecting printing of accumulative sub-totals from the accumulators on which normal total printing has been suppressed.

19. A tabulating machine including a plurality of accumulators and printing mechanism associated therewith, total control mechanism and means for selectively coordinating any of said accumulators with said printing mechanism through said control mechanism to effect total printing in connection with any accumulators and additional selective control mechanism for effecting printing of accumulative sub-totals in connection with accumulators not selected for normal total printing.

In testimony whereof I hereto affix my signature.

CLAIR D. LAKE.
